[57] CLAIM

The ornamental design for a snow brush with removable scraper, as shown and described.

DESCRIPTION

FIG. 1 is a top plan view of a snow brush with removable scraper showing my new design;

FIG. 2 is a bottom plan view thereof;

FIG. 3 is a side elevational view thereof, the opposite side being a mirror image;

FIG. 4 is a front end elevational view thereof;

FIG. 5 is a rear end elevational view thereof;

FIG. 6 is an exploded side elevational view thereof, shown with the scraper removed;

FIG. 7 is a bottom plan view of the scraper shown separately for clarity of illustration only;

FIG. 8 is a top perspective view of the snow brush with removable scraper of FIG. 1; and,

FIG. 9 is a bottom perspective view of the snow brush with removable scraper as shown in FIG. 1.

FIG. 1A

FIG. 1B

FIG. 2A

FIG. 2B

FIG. 3A

FIG. 3B
